UNITED STATES PATENT OFFICE

CHARLES E. VAWTER, OF PHILADELPHIA, PENNSYLVANIA

DESIGN FOR AN ELECTRIC LIGHTER

Application filed August 27, 1929. Serial No. 32,561. Term of patent 14 years.

To all whom it may concern:

Be it known that I, CHARLES E. VAWTER, a citizen of the United States, residing at 6700 Cresheim Road, Philadelphia, county of Philadelphia, State of Pennsylvania, and whose post-office address is 6700 Cresheim Road, Philadelphia, Pennsylvania, have invented a new, original, and ornamental Design for an Electric Lighter, of which the following is a specification, reference being had to the accompanying drawing, forming a part hereof.

Fig. 2 shows the design in side elevation.

I claim:

The ornamental design for an electric lighter, as shown.

CHARLES E. VAWTER.
